UNITED STATES PATENT OFFICE

118,649

DESIGN FOR A HEATER CABINET

Herbert M. Reeves, Kankakee, Ill., assignor to Florence Stove Company, Gardner, Mass., a corporation of Massachusetts

Application September 18, 1939, Serial No. 87,265

Term of patent 3½ years

To all whom it may concern:

Be it known that I, Herbert M. Reeves, a citizen of the United States, residing at Kankakee, in the county of Kankakee and State of Illinois, have invented a new, original, and ornamental Design for a Heater Cabinet, of which the following is a specification, reference being had to the accompanying drawing, forming a part thereof.

Fig. 1 is a perspective view of a heater cabinet embodying my new design.

Fig. 2 is a top plan view of the same.

I claim:

The ornamental design for a heater cabinet, substantially as shown.
